UNITED STATES PATENT OFFICE

2,481,883

PUNCH APPARATUS

Loren H. Semler, Chicago, Ill., assignor to Metal Specialties Manufacturing Co., Chicago, Ill., a corporation of Illinois

Application September 24, 1947, Serial No. 775,901

5 Claims. (Cl. 164—91)

1

This invention relates to punch apparatus. The invention is particularly useful as a punch for paper and especially sheets for looseleaf notebooks, etc.

An object of the invention is to provide a punch structure of novel design providing extreme accuracy in adjustment and which is highly effective in the punching of sheets and the like. A further object is to provide a structure in which a cover for the punch is utilized in providing a rocker rib simultaneously actuating the punch plungers. Yet another object is to provide a punch structure in which separate punch frames are releasably mounted therein in alignment with vertical and horizontal grooves for purposes herein-after set forth. Other specific objects and advantages will appear as the specification proceeds.

The invention is illustrated, in a single embodiment, by the accompanying drawing, in which—

Fig. 1 is a perspective view of a punch structure embodying my invention; Fig. 2, a top plan view; Fig. 3, a front view in elevation; and Fig. 4, a transverse sectional view on an enlarged scale.

In the illustration given 10 designates a punch casing having the cross-sectional shape illustrated best in Fig. 4. The casing provides a vertical backstrip 11 having spaced horizontal slots 12 therein. The casing is provided with downwardly struck channels or ribs 13 and 14 and between the ribs extends a relatively flat raised web 15. The web 15 is provided with spaced slots 16. At its forward end, the casing 10 is provided with a downwardly inclined wall 17 which extends to a point in line with the bottom of the ribs 13 and 14. The downwardly inclined wall 17 carries a scale 18, as shown more clearly in Figs. 1 and 3.

The rear wall 11 of casing 10 is provided with rearwardly and upwardly extending ears 19 having slots 20 therein. The slots 20 of ears 19 receive the metal loops 21 carried by the cover member 22 and thus the loops and ears provide hinges for pivotally supporting the cover 22 upon the casing 10.

The cover 22 is made of sheet metal and is provided with at least one longitudinal rib 23 aligned for cooperation with the punch plunger below. The cover 22 extends forwardly over the punches and over the casing 10 thus providing protection for the structure below while at the same time providing a means for actuating the individual punches as will be hereinafter described.

Mounted over each of the horizontal slots 16 is a punch frame 24. The punch frame is formed by metal strip bent upon itself, as shown more clearly in Fig. 4. The upper portion of the struc-

2

ture is in substantially the shape of a rectangle, the leg on one side being extended below to form a base 25. The platform or base 25 extends between the rear wall 11 and engages the raised forward wall 26 adjacent the inclined edge 17, as shown more clearly in Fig. 4. The top wall of the member 24 is provided with a reduced opening 27 while the remaining two walls there below are provided with the openings 28 and 29. A plunger 30 is adapted to extend through the openings 28 and 29 and is provided at its top with a reduced extension 31 extending through the opening 27. The top of extension 31 is provided with a button 32 secured to the extension 31 by the rounded rivet head 33. The rounded rivet head 33 engages the longitudinal rib 23 of the cover 22 so as to provide a rocker contact therewith. The opening 28 in the base 25 of member 24 is aligned with the longitudinal opening 16 in the lower frame wall 15, as shown more clearly in Fig. 4. The depending ribs 13 and 14 provide a chamber below the platen 15 to receive segments struck out from paper, etc., by the punch plunger 30.

Each of the punch frames 24 is provided with a threaded aperture at its rear to receive a screw 34 carried by the knurled head 35. The knurled head 35 may be provided with a cross-slot 36 to receive the edge of a screwdriver.

Operation

In the operation of the device, the individual punch frames 24 are adjusted with respect to the scale 18 so that they are exactly at the right distance for the punching of holes in the paper. Tightening of the screw heads 35 is then effected by a screwdriver or by turning the head with one's fingers and in this way the punches 24 are securely locked in the selected position. Paper may be pushed forwardly and is guided by the inclined surface 17 onto the base 25 of the punch frame 24. One edge of the paper is brought against a stop 37 at one end of the punch so that the paper is properly aligned. It will be understood that the stop 37 may be made adjustable for extension to any desired distance beyond the frame wall 15. During the preliminary operation described, the cover 22 is preferably swung to a rear position so as to entirely expose the punches and the forward edge portion of the apparatus. To punch the paper, the cover 22 is drawn forwardly and downwardly, providing leverage by which each of the plungers 30 is caused to pass through the paper below. In the downward movement of the cover 22, the rib 23 thereof rocks upon the top of the plunger 30 so that a smooth operation occurs, the

rib serving also as a means for strengthening the sheet metal cover at the point of strain over each of the plungers. Additional longitudinal ribs may be provided if desired to strengthen and stiffen the cover.

A spring 38 extends between each of the plunger heads 32 and the top wall of the punch frame 24 and urges the plunger upwardly against the cover, maintaining the cover normally in the slightly tilted position illustrated in Fig. 4.

Each of the frame members 23 is rigidly held in the position illustrated in Fig. 4. The screw clamp 34 draws the rear wall of the frame 24 against the wall 11 of the frame and the lower base wall 24 is confined between the forward shoulder 26 of the front edge 17 and the rear wall 11.

When it is desired to change the spacing, the knurled head 35 may be rotated preferably by a screwdriver to release the frame 24 for sliding movement. The frame 24 is then moved laterally so as to bring a marker line on the front thereof into alignment with a selected line on the scale. The head 35 may then be turned in the opposite direction to lock the punch frame securely in position, as already described.

In the illustration given, the cover 22 is provided with a forwardly extending central portion so as to enable the operator to center the pressure applied to the cover and also to provide greater leverage at such central portion.

The punching operation is extremely smooth and even, the rounded rib 23 of the cover providing a rocking engagement with the plunger which moves in a straight vertical direction.

The ribs 13 and 14 not only strengthen the bottom wall, but also provide a clearance for the paper punchings. The cover 22 above the casing 10 is pivoted upon hinges not only for the purpose of actuating the plungers but also for providing an opening to gain access to the punches. The threaded locking members 34 may be manipulated very quickly for the removing of the separate punch frames 24, the slot 36 being large enough to be operated by a coin in lieu of a screw driver. Nine punches have been used successfully in a single apparatus and it will be understood that the number may be varied as desired.

For repair or replacement, any one of the punch frames can be quickly removed. The insertion of a repaired or new punch can be accomplished in a few moments and the punch is again ready for operation.

While in the foregoing specification, I have set forth one embodiment of the invention in considerable detail for the purpose of illustrating the invention, it will be understood that such details of structure may be varied widely by those skilled in the art without departing from the spirit of my invention.

I claim:

1. In a punch structure of the character set forth, a frame, punch plungers mounted for vertical reciprocation in said frame, springs urging said plungers toward elevated position, and a frame cover pivotally mounted on said frame and adapted to engage the upper ends of said plungers, said cover being provided with a longitudinal channel providing rounded bottom bearings adapted to rock upon the upper end portions of said plungers.

2. In a punch structure of the character set forth, a main frame providing a vertical rear wall, a horizontal bottom wall, and a slightly elevated front wall having an outer and down-

wardly inclined edge, said bottom wall and said vertical wall being provided with elongated slots, a plurality of punch frames having base walls snugly received between said rear wall and said forward shoulder, said punch frame also having a pair of spaced walls apertured to receive a plunger and said base wall being also apertured in alignment with the apertures in said bottom wall of the main frame, punch plungers within 10 said recesses of the punch frame, spring means normally urging said plungers upwardly, said punch frames also having tapped openings in the rear walls thereof, threaded means extending through the slots of the main frame wall and 15 engaging said tapped openings of the punch frames to lock said frames in position, and a cover pivotally mounted upon the rear wall of said frame and adapted to be lowered to engage simultaneously all of said plungers.

3. In punch structure of the character set forth, a main frame providing a vertical rear wall, a horizontal bottom wall, and a slightly elevated front wall having an outer and downwardly inclined edge, said bottom wall and said vertical wall being provided with elongated slots, a plurality of punch frames having base walls snugly received between said rear wall and said forward shoulder, said punch frame also having a pair of spaced walls apertured to receive a plunger and 25 said base wall being also apertured in alignment with the apertures in said bottom wall of the main frame, punch plungers within said recesses of the punch frame, spring means normally urging said plungers upwardly, said punch frames 30 also having tapped openings in the rear walls thereof, threaded means extending through the slots of the main frame wall and engaging said tapped openings of the punch frames to lock said frames in position, and a cover pivotally mounted 35 upon the rear wall of said frame and adapted to be lowered to engage simultaneously all of said plungers, said cover being provided with at least one longitudinal channel providing rounded bottom bearings adapted to rock upon the upper ends 40 of said plungers upon swinging movement of said cover.

4. In a punch structure of the character set forth, a main casing providing a vertical rear wall, a horizontal bottom wall and a downwardly inclined front edge wall, said bottom wall of the casing being pressed downwardly to provide depending legs for supporting the bottom wall above the surface upon which the apparatus rests, said bottom wall and said rear wall being provided 50 with elongated slots, said rear wall being also provided with rearwardly and upwardly extending ears having slots therein, a cover having metal loops engaging the slots of said ears, a scale carried by the forward edge of said main casing, a 55 plurality of punch frames slidably mounted on said bottom wall of the main frame and alignable with points on said scale, said frame having vertical slots extending therethrough, in alignment with the bottom slots of said main frame, 60 plungers mounted for reciprocation in the openings of said punch frames, springs normally urging said plungers toward elevated position where they are adapted to engage said cover, said punch frames having threaded recesses in the rear wall 65 thereof, and threaded bolt members extending through the slots in the rear wall of said frame and threadedly engaging the recesses of said punch frames to lock said punch frames in the selected position.

5. In a punch structure of the character set

forth, a main casing providing a vertical rear wall, a horizontal bottom wall and a downwardly inclined front edge wall, said bottom wall of the casing being pressed downwardly to provide depending legs for supporting the bottom wall above the surface upon which the apparatus rests, said bottom wall and said rear wall being provided with elongated slots, said rear wall being also provided with rearwardly and upwardly extending ears having slots therein, a cover having metal loops engaging the slots of said ears, a scale carried by the forward edge of said main casing, a plurality of punch frames slidably mounted on said bottom wall of the main frame and alignable with points on said scale, said frame having vertical slots extending therethrough in alignment with the bottom slots of said main frame, plungers mounted for reciprocation in the openings of said punch frames, springs normally urging said plungers toward elevated position where they are adapted to engage said cover, said punch frames having threaded recesses in the rear wall thereof,

and threaded bolt members extending through the slots in the rear wall of said frame and threadedly engaging the recesses of said punch frames to lock said punch frames in the selected position, said cover being provided with a longitudinal rib aligned with said plungers and providing a rounded bottom surface adapted to rock upon the upper ends of said plungers when said cover is moved downwardly in the punching structure.
